CIRCUIT ARRANGEMENT FOR PRODUCING
A HIGH-FREQUENCY OSCILLATION

Eduard Herman Hugenholtz, Eindhoven, Netherlands, assignor to Hartford National Bank and Trust Company, Hartford, Conn., as trustee

Application October 19, 1948, Serial No. 55,262
In the Netherlands October 24, 1947

6 Claims. (Cl. 250—36)

1

This invention relates to circuit-arrangements for producing a high-frequency oscillation, of which the frequency is variable in accordance with a control voltage supplied to the control grid of a regeneratively back-coupled discharge tube. It has more particularly for its purpose to provide a very simple circuit-arrangement for frequency-modulation or after-adjustment of the frequency of a high-frequency oscillation.

In a known circuit-arrangement of this type, in which only one discharge tube is used, the cathode-circuit of this regeneratively back-coupled tube comprises a resistance, a reactance being provided between cathode and grid. Due to this the phase displacement conferred on the high-frequency alternating voltage supplied to the grid of the tube depends upon the high frequency voltage across the cathode resistance. Since a modulating control voltage influencing the mutual conductance of the discharge tube is at the same time supplied to the said grid, so that the high-frequency voltage across the cathode-resistance is varied, the variable phase shift thus produced will cause a variation of the frequency produced by means of the circuit-arrangement.

However, this circuit-arrangement suffers from the disadvantage that, since the effective mutual conductance of the discharge tube is not altered by a variation of the grid bias, the value of a high-frequency voltage across the cathode resistance depends only to a small degree upon the value of the modulating control voltage, so that the oscillation produced is variable in frequency to a low degree only. This disadvantage might be avoided, for instance by making the modulating control voltage operative in the anode-circuit of the discharge tube. In this event, however, the required control voltage should be much higher and in addition the source of control voltage must supply anode current for the discharge tube, which entails a complicated circuit-arrangement.

The invention provides a different arrangement which permits by simple means a high-frequency oscillation to be produced of which the frequency is variable with the aid of a regulating voltage supplied to the grid of the discharge tube. It has the advantages that the said control is effected substantially without loss of energy and that considerable frequency variations are possible. In one form of the circuit-arrangement according to the invention the additional advantage is obtained that the amplitude of the alternating voltage supplied to the grid of the discharge tube remains substantially constant, which permits the mutual conductance to be greatly varied.

2

According to the invention the feedback circuit of the discharge tube comprises a voltage discriminative impedance of which the value varies in accordance with the amplitude of the alternating voltage generated in the anode circuit of the discharge tube, as a result of which a phase-shift of the high-frequency alternating voltage is produced across this impedance, which shift involves a frequency variation of the oscillation produced.

10 In order that the invention may be clearly understood and readily carried into effect it will now be explained more fully with reference to the accompanying drawing given by way of example.

In the drawing the reference numeral 1 denotes 15 a discharge tube which is regeneratively fed back by way of the tuned circuit 2 and coupled inductance 3 with the result that a high-frequency oscillation is produced, of which the frequency corresponds approximately to the natural resonance

20 of the tuned oscillating circuit 2 if the network inserted in the said anode circuit of tube 1 and comprising a small condenser 4 and a voltage discriminative impedance, for example a biased diode 5, would not produce a phase-shift of the

25 oscillation supplied to the circuit 2. If the amplitude of the voltage produced in the anode circuit is small so that the diode 5 does not carry current, this will be the case since a small condenser 6 is connected in parallel with the diode 5. A modulating voltage is at the same time supplied, 30 by way of the terminals 7, to the grid of the discharge tube 1. The high-frequency voltage produced in the anode circuit of the discharge tube 1 will increase with an increase in modulating voltage, owing to which the diode 5 carries current.

35 In this event this diode 5 constitutes a resistance in parallel with the condenser 6 with the result that the voltage fed to the circuit 2 is shifted in phase. Due to this the frequency of the oscillation produced will adjust itself to a different

40 value, since the total phase displacement of the high-frequency voltage between grid and anode must be 180° . The choke coils 8 and 9 permit the passage of direct current and have a high impedance to high-frequency currents. The embodiment described offers the additional advantage

45 that the amplitude of the voltage produced across the oscillating circuit 2, and consequently also the amplitude of the alternating grid voltage of the discharge tube 1 acquires a constant value, thus

50 avoiding the disadvantage that by varying the grid-adjustment of the discharge tube 1 with the aid of the modulating voltage 7 such a variable alternating anode voltage is produced that the effective mutual conductance of this tube should 55 remain substantially the same.

The diode 5 may be replaced by a different voltage discriminative impedance, for example a rectifying cell. Furthermore, this impedance need not be inserted in the anode circuit of the discharge tube 1 but may, in general, be inserted at an arbitrary point in the circuit-arrangement by which it brings about a phase shift of the high-frequency voltage, which depends upon the modulating voltage.

What I claim is:

1. Apparatus for producing high-frequency oscillations whose frequency varies in accordance with the instantaneous amplitude of a control voltage comprising an electron discharge tube provided with a cathode, a grid and an anode, a resonant circuit coupled between said anode and said cathode, a feedback circuit regeneratively coupling said resonant circuit to said grid to sustain high-frequency oscillations in said resonant circuit, a phase-shifting network interposed between said anode and said resonant circuit and including an impedance element whose value depends on the amplitude of oscillations imposed on said network, the value of said impedance element determining the extent of phase-shifting imparted by said network, and means to apply said control voltage to said grid thereby to vary the amplitude of oscillations imposed on said network, whereby the frequency of said oscillations is varied in accordance with the instantaneous amplitude of said control voltage.

2. Apparatus, as set forth in claim 1, wherein said impedance element is constituted by a rectifying device.

3. Apparatus for producing high-frequency oscillations whose frequency varies in accordance with the instantaneous amplitude of a control voltage comprising an electron discharge tube provided with a cathode, a grid and an anode, a resonant circuit coupled between said anode

30

40

and said cathode, inductive means regeneratively coupling said resonant circuit to said grid to sustain high-frequency oscillations in said resonant circuit, means to apply the control voltage to said grid to vary the amplitude of said oscillations, and a phase-shifting network interposed between said anode and said resonant circuit and including an impedance element whose value determines the characteristics of said network and depends on the amplitude of oscillations applied thereto.

4. An arrangement, as set forth in claim 3, wherein said network is constituted by a capacitor coupled between said anode and one end of said resonant circuit and a diode having an anode coupled to said one end of said resonant circuit and a cathode coupled to the other end thereof.

5. An arrangement, as set forth in claim 4, further including a bias source whose negative terminal is connected to the anode of said diode and whose positive terminal is connected to the cathode of said diode.

6. An arrangement, as set forth in claim 5, further including a radio frequency choke interposed between the anode of said diode and said negative terminal.
